UNITED STATES PATENT OFFICE.

PAUL DVORKOVITZ, OF NORTH KENSINGTON, LONDON, ENGLAND.

APPARATUS FOR MANUFACTURE OF WATER GAS.

Application filed August 30, 1924. Serial No. 735,121.

To all whom it may concern:

Be it known that I, PAUL DVORKOVITZ, a Russian subject, residing at North Kensington, in the county of London, England, 5 have invented new and useful Apparatus for Manufacture of Water Gas, of which the following is a specification.

This invention relates to apparatus for use in the manufacture of water gas in which coke, coal, or other carbonaceous matter, in a finely divided condition is subjected to the action of heat in the presence of highly superheated steam alone or steam with the addition of hydrogen or oxygen, 10 separately or combined, which is obtained by heat applied by passing steam through passages heated by hot gases passing from a chamber, or vessel, in which the coal, coke, or other carbonaceous matter under treatment 15 is maintained at a temperature sufficient to cause the steam or the steam and gas mixture which passes through the said passages, to become highly superheated. The superheated steam or the steam and gas mixture enters the upper part of the said chamber, or vessel, and there meets with the finely divided coke, coal, or other carbonaceous matter, which passes downward with the steam or steam and gas mixture, producing water gas which passes off to any 20 suitable receptacle, or place of utilization.

According to my invention the chamber, or vessel, through which the finely divided coke, coal, or other carbonaceous matter, 25 and the steam or steam and gas mixture pass downwards is provided with a deflector, or deflectors (hereinafter referred to as a deflector) against which the finely divided carbonaceous matter is projected by a suitably shaped hopper so that the said carbonaceous matter is dispersed. The deflector is so situated, or arranged, that the superheated steam alone or with the addition of 30 hydrogen or oxygen separately or combined, entering the said chamber, or vessel, impinges upon the said deflector and meets, at a high velocity and pressure, the dispersed carbonaceous matter whereby the oxygen of the superheated steam or steam and gas mixture combines more readily and effectively 35 with the carbon of the coke, coal, or other carbonaceous matter under treatment so that carbonic oxide is formed and mixes with the free hydrogen.

55 The finely divided coke, coal, or other carbonaceous matter, is, if necessary, or desir-

able subjected to preliminary heating to remove moisture, and other volatile matter, before the said matter is admitted to the aforesaid chamber, or vessel, to meet the 60 superheated steam alone or steam and hydrogen and oxygen mixture which is admitted at, or near, the top of the said chamber, or vessel, the steam or steam and gas mixture having been submitted to a temperature, usually from 1,000° to 1,100° Centigrade, (but which may be from 950° to 1,200° Centigrade), which it has derived from the incandescent matter in the aforesaid chamber, or vessel. 70

At such temperatures the oxygen has great oxidizing effect on the powdered carbonaceous matter and, the said matter being in excess of the oxygen present, carbon monoxide gas is produced. 75

The aforesaid chamber, or vessel, may be divided into two vertical parts in the first of which, by means of a blower for instance, carbonaceous matter is heated to incandescence the hot gases then passing through the 80 second part of the said chamber, or vessel, and thence, if so desired, into a preheater. When the requisite heat is attained the blowing will be stopped and steam or steam and gas mixture be admitted so that it takes up the heat obtained as aforesaid from the incandescent fuel and is superheated and passes into the aforesaid vessel where it meets the finely divided fuel and water gas is produced. 85

90 I will describe, with reference to the accompanying drawing, an apparatus and mode of operation which will explain how my invention can be carried into effect, employing steam as a source of the oxygen and hydrogen, but I do not limit myself to the precise details hereinafter explained with reference to this drawing.

95 In the said drawing I have shown the apparatus, in Figure 1 in vertical section, and in Figure 2 in horizontal section.

The vessel A is divided into two vertical chambers by the wall B, the first chamber (C) constituting the generator and the second chamber (D) containing checker-work 105 or other arrangement of refractory material and constituting a superheater. The generator C is provided, at, or near, its lower end with fire-bars a^1 and a valve-controlled air inlet a^1 and, at or near the top, with a hopper a^2 (also valve-controlled) through 110 which the finely divided carbonaceous mat-

ter employed passes, it impinging upon a deflector a^3 . Towards the lower part of the generator C is a valve-controlled passage a^4 for the outlet of the produced water 5 gas and towards the upper part of the wall B, opposite the deflector a^3 is a passage b , through which the highly superheated steam resulting from the heating of the steam in the superheater D passes into the said 10 generator. Near to, or adjoining, the superheater D, is a preheater E at, or near to, the upper part of which steam alone or steam with the addition of hydrogen or oxygen gas separately or combined is admitted 15 through a pipe e , the said preheater containing checkerwork, or other arrangement of refractory material in contact with which the steam or steam and gas mixture passes on its way to the superheater through the 20 pipe e^1 constituting a communicating passage between the lower parts of the preheater and superheater. The preheater E, is provided with a hinged top, or cover, e^2 capable of being opened by any suitable 25 means, such for example, as a counter-weighted chain e^3 , the weight being such that the cover will return to its closed position when the chain is released.

The operation is as follows:—Carbonaceous matter having been delivered, through 30 the hopper a^2 or otherwise, onto the bars a , the valve of the water-gas outlet a^4 is closed and the hinged cover e^2 of the preheater E is opened. Air is then forced, by any suitable 35 means, through the inlet a^1 into the generator C until the said carbonaceous matter is heated to incandescence, the hot gases passing through the passage b into the superheater D, and thence through the pipe 40 e^1 into the preheater E. When the requisite heat is attained the blowing in of air will be discontinued, the valve controlling the water-gas outlet a^4 will be opened and the cover e^2 of the preheater E will be 45 closed. Steam or steam and gas mixture is then admitted through the pipe e into the preheater E from which the said steam or

steam and gas mixture passes, through the pipe e^1 , into the superheater D, where it takes up heat and passes through the passage b on to the deflector a^3 in the generator C where the steam or steam and gas mixture from the superheater meets the finely divided fuel which is being projected from the hopper a^2 on to the deflector. 50

By the employment of apparatus in accordance with my invention water gas can be efficiently obtained from carbonaceous matter which hitherto has not been considered suitable for use in the manufacture, although the said apparatus is also capable of treating carbonaceous matter generally, such, for instance, as coal of various kinds, or coke, obtained from distillation of coal, but including carbonaceous matter which is 60 unsuited for use in the usual way of manufacturing water gas. For instance the apparatus can be employed in the production of water gas by treating soft coke such as that which remains after coal, or other carbonaceous matter, has been treated in accordance with the process described and claimed in my co-pending application for Patent Ser. No. 594,865 filed October 16, 1922. 65

What I claim is:—

Down-run apparatus for the manufacture of water gas from carbonaceous matter in a finely divided condition; having a generator chamber and a superheater chamber 80 associated therewith, said generator chamber having an inlet from the superheater chamber in the upper part of its wall, and a deflector in the generator chamber on the upper part of its wall opposite the inlet and adapted to cause simultaneous deflection of 85 steam or steam and gas mixture from the inlet and the carbonaceous matter, and means adapted to project said carbonaceous matter on to said deflector. 90

In testimony whereof I have signed my name to this specification.

PAUL DVORKOVITZ.
